PASSENGER VEHICLE BODY

Robert R. Larsen, Bloomfield Hills, Mich., assignor, by
mesne assignments, to Transportation Technology, Inc.,
Madison Heights, Mich., a corporation of Delaware

Filed June 23, 1969, Ser. No. 17,820

Term of patent 14 years

Int. Cl. D12—03

U.S. Cl. D66—1

Fig. 1

Fig. 2

Fig. 3

FIG. 1 is a side elevational view of a passenger vehicle body incorporating my new design;

FIG. 2 is a plan view of the passenger vehicle body as viewed on line 2—2 of FIG. 1;

FIG. 3 is an end view of the passenger vehicle body as viewed on line 3—3 of FIG. 1, a view from the opposite direction toward the opposite end being identical; and

FIG. 4 is a perspective view of the passenger vehicle body.

I claim:

The ornamental design for a passenger vehicle body, substantially as shown and described.
